UNITED STATES PATENT OFFICE.

WILLIAM RAILTON AND RICHARD CAMPBELL, OF LIVERPOOL, ENGLAND.

DESIGN FOR A VALVE-CASING.

SPECIFICATION forming part of Design No. 26,683, dated February 23, 1897.

Application filed February 12, 1896. Serial No. 579,086. Term of patent 14 years.

To all whom it may concern:

Be it known that we, WILLIAM RAILTON and RICHARD CAMPBELL, subjects of the Queen of Great Britain, residing at Liverpool, 5 in the county of Lancaster, in the Kingdom of England, have invented a new and original Design for Twin Valves, of which the following is a specification.

This invention relates to a new design for 10 valve-casings, the formation and configuration being shown in the accompanying drawing.

It comprises a central body portion A of 15 substantially elliptical form in horizontal section, from both ends of which extends a cylindrical portion a a', and upon these portions are secured or formed plates B B'. The under portion of the valve-casing near each

end is provided with two cylindrical extensions b b', upon which are secured or formed 20 plates C C'. The under face of the valve-casing immediately between the extensions b b' is given an upward inclination.

Having thus described our invention, what we claim is—

The design for a valve-casing substantially 25 as shown and described.

In testimony whereof we have signed our names to this specification in the presence of two subscribing witnesses.

W. RAILTON.
R. CAMPBELL.

Witnesses:

G. C. DYMOND,
W. H. BEESTON.
